CLAIM

The ornamental design for a container for hair care composition, as shown and described.

DESCRIPTION

FIG. 1 is a perspective view of a container for hair care composition, embodying our new design;

FIG. 2 is a front view of the container for hair care composition of FIG. 1;

FIG. 3 is a first side view of the container for hair care composition of FIG. 1;

FIG. 4 is a back view of the container for hair care composition of FIG. 1;

FIG. 5 is a top view of the container for hair care composition of FIG. 1; and,

FIG. 6 is a bottom view of the container for hair care composition of FIG. 1.

Our design resides in a container for a hair care composition wherein certain portions are opaque and certain portions are transparent. Conventional transparency shading is utilized for the transparent portions. Another embodiment may have the top surface of the transparent section may have a design included on the top surface.
